UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed March 26, 1930. Serial No. 439,187.

This invention relates to mining machines and more particularly has reference to improvements in the feeding mechanism of such machines.

5 An object of this invention is to provide an improved mining machine feeding mechanism. Another object is to provide an improved flexible feeding mechanism wherein a feed operating member cooperating with a 10 flexible feeding element effects feed of the machine. A further object is to provide an improved feed member controlling means whereby the feed member may be entirely disconnected from its drive mechanism in an 15 improved manner. Yet another object is to provide an improved mining machine feeding mechanism wherein the feed member is driven under the control of a clutch and has associated therewith improved means for entirely 20 relieving the feed member from the action of the clutch. Another object is to provide in a mining machine feeding mechanism wherein the feed member is driven under the control of multiple disc clutches, 25 proved clutch devices controlled by the operating means for the disc clutches for entirely disconnecting the feed member from its drive upon release of the multiple disc clutches, thereby relieving the feed member entirely 30 from the action of the clutch discs to permit free rotation of the feed member. These and other objects and advantages of this invention will, however, hereinafter more fully appear.

35 In the accompanying drawing there is shown for purposes of illustration one form which the invention may assume in practice.

In this drawing,—

Fig. 1 is a plan view, partially shown in 40 horizontal section, of an illustrative embodiment of the improved feeding mechanism.

Fig. 2 is a detail vertical section view taken substantially on line 2—2 of Fig. 1.

Fig. 3 is a detail sectional view illustrating 45 the operating means for the speed controlling clutches.

Fig. 4 is a detail sectional view illustrating one of the clutch plungers shown in Fig. 2 in transverse section.

50 In this illustrative embodiment of the in-

vention the improved feed member controlling means is shown embodied in a mining machine feeding mechanism of the same general character as that disclosed in my copending application Ser. No. 367,894, filed June 3, 1929. This feeding mechanism generally comprises a feed frame section 1 having journaled thereon feed operating and controlling members 2 and 3 herein in the form of cable winding or haulage drums driven through a plural speed selective transmission from a motor 4. As described in the application mentioned above, the motor 4 is adapted to effect drive, through the selective transmission, of the feed members in winding direction either separately or simultaneously at relatively high speed or at relatively low speed. The transmission mechanism between the motor and each of the feed drums is substantially identical in structure and therefore a description of one will suffice. As shown in Fig. 1, fixed to the motor shaft 5 is a spur pinion 6 driving through an intermediate gear 7 a spur gear 8 fixed to a horizontal longitudinally extending shaft 9. Fixed to this shaft 9 in longitudinally spaced relation thereon and driven by the shaft are coaxial worms, one of which is designated 10. The worm 10 meshes with a worm wheel 11 fixed to a vertical shaft 12 which drives a worm 13 meshing with a slow speed worm wheel 14 journaled on a transversely extending horizontal hollow shaft 15 suitably journaled within the feed frame section. Arranged coaxially within and rotatably supported by the hollow shaft 15 and connectible with the hollow shaft in an improved manner as hereinafter described is a shaft 16 having secured thereto a spur pinion 17 meshing with an internal gear 18 secured to the feed drum. The other coaxial worm (which is not shown in the drawing) meshes directly with a fast speed worm wheel 19 likewise journaled on the hollow shaft 15. These worm wheels 14 and 19 are alternatively connectible with the hollow shaft 15 by multiple disc clutches 20 and 21 respectively. It will thus be seen that when one or the other of the disc clutches 20, 21 is applied and the shaft 16 is connected for rotation with the hollow shaft 15, the feed

drum may be driven in winding direction at relatively high speed or at relatively low speed, depending upon which of the disc clutches is applied.

Now referring to the improved operating means for the friction clutches and more particularly to the improved means controlled thereby for connecting the shafts 15, 16 together, it will be noted that interposed between the clutches and surrounding the shaft 15 is a clutch applying member 22 with which a shipper yoke 23 pivoted at 24 on the feed frame section cooperates. This shipper yoke has a lateral arm 25 projecting within a notch or recess 26 formed in a slidable actuating rod 27. This rod is slidably guided within the feed frame section and is splined at 28 to the feed frame to prevent rotation thereof about its axis. This rod is threaded at 29 throughout a portion of its length and is connected to a rotatable adjusting nut 30 rotatably supported by the feed frame. Formed on this nut is a bevel gear 31 meshing with a bevel gear 32 fixed to a longitudinally extending shaft 33 rotatably supported within a bracket 34 secured to the rear end wall of the feed frame. Secured to the outer end of this shaft is an operating handle 35. The clutch applying member 22 is connected through an antifriction bearing 36 to an annular clutch member 37 slidably mounted on an enlarged cylindrical portion 38 formed on the hollow shaft 15 intermediate its ends. The end surfaces of the member 37 are adapted to engage plungers 39 carried within the adjacent vertical end plates of the worm wheels 14, 19. When the clutch applying member is shifted in one direction or the other, one or the other of the sets of plungers 39 is engaged thereby to effect application of the disc clutch. It will thus be seen that when the handle 35 is rotated, rotation of the nut 30 imparts axial movement to the rod 27 in one direction or the other to swing the shipper yoke 23 about its pivot, and as a result, the clutch applying member 22, together with the member 37, are shifted into one or the other of their operating positions. In the present construction, the clutch member 37 is internally grooved at 40 and is provided with oppositely disposed inclined cam surfaces 41 and 42. Projecting within the groove 40 in the clutch member when the latter is in the position shown in Fig. 1 are clutch plungers 43 slidably mounted within radial chambers 44 formed in the enlarged intermediate portion 38 of the shaft 15. Each of these plungers is grooved at 45 at its opposite sides to form recesses within which springs 46 are arranged, the latter tending to hold the clutch plungers 43 in their outermost or released position. The inner ends of these plungers when in the position shown in Fig. 2, engage slots or grooves 47 cut in the shaft 16. Each

of the clutch plungers is provided with inclined surfaces which are complementary to the inclined cam surfaces on the clutch member 37.

When the parts are in the position shown in Fig. 1, the clutch plungers are held within the annular recess 40 in the member 37 with their inner ends wholly released from the grooves in the shaft 16. When the clutch member 22 is in this position the disc clutches 20 and 21 are both released. At this time, the feed drum may rotate freely relative to its drive mechanism, the shaft 16 upon rotation of the drum turning freely within the hollow shaft 15. When it is desired to effect drive of the feed drum in winding direction at a relatively slow speed, the clutch member 22 is shifted upon suitable manipulation of the operating handle 35 in the direction to cause the inclined cam surface 41 on the member 37 to force the clutch plungers 43 inwardly into interlocking engagement with the grooves on the shaft 16, thereby connecting the shaft 16 to the shaft 15. Upon further movement of the clutch member, the plungers 39 are engaged and the discs of the clutch 20 forced into their engaged position. When the clutch member 22 is shifted in the opposite direction, the friction clutch 21 is released and thereafter the shaft 16 disconnected from the shaft 15. Upon further movement of the clutch member 22 the inclined cam surface 42 moves the clutch plungers into their connected position and thereafter the friction clutch 21 is applied. Heretofore it has been found that without the provision of the clutch devices between the shafts 15, 16 drag rotation was imparted by the clutch discs of the clutches 20, 21, even when the latter were in their released position, which caused the feed drum to rotate. Under certain conditions, for instance when the motor 4 was reversed, it has been found that the drag of the clutch discs, even when in their released position, was sufficient to cause the feed drums to rotate to unwind the feed cables and with some danger of causing the latter to become tangled and twisted. By the provision of the clutch device between the friction clutches and the drive shaft 16 it is possible, when this clutch device is released, to entirely relieve the feed drum from any action of the clutch discs, so that when the clutch operating means is in its neutral position the feed drum remains stationary or may be freely rotated. This is an especially desirable feature when it is desired to unwind the feed cable from the feed drum by hand. These and other uses and advantages of the improved feed drum control means will be clearly apparent to those skilled in the art. While I have in this application specifically described one form which my invention may assume in practice, it will be understood that this form of the same is shown for

purposes of illustration and that the invention may be modified and embodied in various other forms without departing from its spirit or the scope of the appended claims.

What I claim as new and desire to secure by Letters Patent is:

1. In a mining machine feeding mechanism, the combination of a feed member, driving mechanism for said feed member including a controlling clutch and operating means therefor, and separate clutch means controlled by said clutch operating means for insuring disconnection of said feed member from said driving mechanism whenever said clutch operating means is moved into its clutch releasing position.
2. In a mining machine feeding mechanism, the combination of a feed member, driving mechanism therefor including a multiple disc clutch and operating means therefor, and means distinct from said clutch and controllable to establish or interrupt a driving relation and controlled by said clutch operating means for insuring disconnection of said feed member from said driving mechanism whenever said clutch operating means is moved into its clutch releasing position to entirely relieve said feed member from any action of said clutch.
3. In a mining machine feeding mechanism, the combination of a feed member, driving mechanism therefor including a multiple disc clutch and operating means for said clutch, and means distinct from said clutch and controllable to establish or interrupt a driving relation and controlled by said clutch operating means for insuring disconnection of said feed member from said driving mechanism whenever said clutch operating means is moved into its clutch releasing position to relieve said feed member entirely from the action of the discs of said clutch when said clutch is released by said operating means.
4. In a mining machine feeding mechanism, the combination of a feed member, driving mechanism therefor including a multiple disc clutch and operating means for said clutch, and means controlled by said clutch operating means and including a releasable interlocking device for insuring disconnection of said feed member from said driving mechanism whenever said clutch operating means is moved into its clutch releasing position to relieve said feed member from any action of the discs of said clutch when said clutch is released by said operating means.
5. In a mining machine feeding mechanism, the combination of a feed member, driving mechanism therefor including a controlling clutch and releasable interlocking devices in the drive between said clutch and said feed member, and a common operating element for controlling said clutch and said interlocking devices for insuring connection of

said interlocking devices prior to the application of said clutch.

6. In a mining machine feeding mechanism, the combination of a feed member, driving mechanism therefor including a controlling clutch and releasable interlocking devices in the drive between said clutch and said feed member, and a common operating element for controlling said clutch and said interlocking devices, said common control member when moved in one direction first connecting said interlocking devices and thereafter applying said clutch.

7. In a mining machine feeding mechanism, the combination of a feed member, driving mechanism therefor including coaxial relatively rotatable driving elements, means for effecting rotation of one of said elements including a controlling clutch, devices for connecting said elements together for simultaneous rotation, and means for controlling said clutch and said devices insuring connection of said connecting devices prior to the application of said clutch.

8. In a mining machine feeding mechanism, the combination of a feed member, driving mechanism therefor including coaxial relatively rotatable driving elements, means for effecting rotation of one of said elements including a controlling clutch, devices for connecting said elements together for simultaneous rotation, and means for controlling said clutch and said devices and operative to first actuate said devices to connect said elements together and thereafter to apply said clutch in a fixed and definite sequence.

9. In a mining machine feeding mechanism, the combination of a feed member, driving mechanism therefor including coaxial relatively rotatable driving elements, operative driving connections between one of said elements and said feed member, means for effecting rotation of said other element including a controlling clutch coaxial with said elements, devices for connecting said elements together for simultaneous rotation, and common operating means for controlling said clutch and said devices.

10. In a mining machine feeding mechanism, the combination of a feed member, driving mechanism therefor including coaxial relatively rotatable driving elements, operative driving connections between one of said elements and said feed member, means for effecting rotation of said other member including a controlling clutch, devices for connecting said elements together for simultaneous rotation, and means for controlling said clutch and said devices and operative to first actuate said devices to connect said members together and thereafter to apply said clutch in a fixed and definite sequence.

11. In a mining machine feeding mechanism, the combination of a feed member and driving mechanism therefor including coaxial

- ally arranged shafts, means for effecting rotation of one of said shafts including a controlling clutch, devices for connecting said shafts together for simultaneous rotation, and means for operating said clutch and actuating said devices including a common operating element coaxial with said shafts.
12. In a mining machine feeding mechanism, the combination of a feed member, and driving mechanism therefor including coaxially arranged shafts, means for effecting rotation of one of said shafts including a controlling clutch, devices for connecting said shafts together for simultaneous rotation, and means for operating said clutch and actuating said devices and operative to first actuate said devices to connect said shafts together and thereafter to apply said clutch in a fixed and definite sequence.
13. In a mining machine feeding mechanism, the combination of a feed member, and driving mechanism therefor including coaxial relatively rotatable shafts relative to which said feed member is rotatable, operative connections between one of said shafts and said feed member, and means for effecting rotation of the other of said shafts including a controlling clutch coaxial with said shafts and through which power is transmitted to drive the shaft controlled thereby, devices for connecting said shafts together for simultaneous rotation, and common means for operating said clutch and actuating said devices.
14. In a mining machine feeding mechanism, the combination of a feed member, and driving mechanism therefor including coaxial relatively rotatable shafts, operative connections between one of said shafts and said feed member, and means for effecting rotation of the other of said shafts including a controlling clutch, devices for connecting said shafts together for simultaneous rotation, and means for operating said clutch and actuating said devices and operative to first actuate said devices to connect said shafts together and thereafter to apply said clutch in a fixed and definite sequence.
15. In a mining machine feeding mechanism, the combination of a feed member, and driving mechanism therefor including a plurality of controlling clutches, one operative to effect drive of said feed member at one speed and the other at a different speed, devices coaxial with said clutches and between said clutches and said feed member for connecting the latter to its drive, and common means for controlling said clutches and actuating said devices.
16. In a mining machine feeding mechanism, the combination of a feed member, and driving mechanism therefor including a plurality of controlling clutches, one operative to effect drive of said feed member at one speed and the other at a different speed, de-
- vices between said clutches and said feed member for connecting the latter to its drive, and means for controlling said clutches and actuating said devices and operative, in a fixed and definite sequence, first to actuate said devices to connect said feed member to its drive and thereafter to apply one or the other of said clutches.
17. In a mining machine feeding mechanism, the combination of a feed member, and driving mechanism therefor including coaxial relatively rotatable elements, means for effecting rotation of one of said elements at either of two speeds including a plurality of controlling clutches, devices coaxial with said clutches for connecting said coaxial elements together for simultaneous rotation, and common means for actuating said devices and controlling said clutches.
18. In a mining machine feeding mechanism, the combination of a feed member, and driving mechanism therefor including coaxial relatively rotatable elements, means for effecting rotation of one of said elements at either of two speeds including a plurality of controlling clutches, devices for connecting said coaxial elements together for simultaneous rotation, and means for actuating said devices and controlling said clutches and operative, in a fixed and definite sequence, first to first actuate said devices to connect said elements together and thereafter to apply one or the other of said clutches.
19. In a mining machine feeding mechanism, the combination of a feed member, and driving mechanism therefor including coaxial relatively rotatable shafts, driving connections between one of said shafts and said feed member, mechanism for effecting rotation of said other shaft at either of two speeds including a plurality of controlling clutches coaxial with said shafts, devices for connecting said shafts together for simultaneous rotation, and common means for actuating said devices and for controlling said clutches.
20. In a mining machine feeding mechanism, the combination of a feed member, and driving mechanism therefor including coaxial relatively rotatable shafts, driving connections between one of said shafts and said feed member, mechanism for effecting rotation of said other shaft at either of two speeds including a plurality of controlling clutches, devices for connecting said shafts together for simultaneous rotation, and means for actuating said devices and for controlling said clutches and operative, in a fixed and definite sequence, first to first actuate said devices to connect said shafts together and thereafter to apply one or the other of said clutches.
21. In a mining machine feeding mechanism, the combination of a feed member, driving mechanism therefor including a controlling clutch and connecting devices in the drive between said clutch and said feed member,

and a common operating element for controlling said clutch and said connecting devices, said common controlling operating element when moved in one direction first connecting 5 said connecting devices and thereafter applying said clutch.

22. In a mining machine feeding mechanism, the combination of a feed member, driving mechanism therefor including relatively 10 rotatable transmission elements, operative connections between one of said elements and said feed member, means for effecting rotation of the other element including a friction controlling clutch, means including interlocking 15 clutch plungers for connecting said transmission elements directly together, and clutch controlling means for insuring release of said friction clutch and thereafter release of said clutch plungers to permit free relative rotation 20 between said transmission elements.

23. In a mining machine feeding mechanism, the combination of a feed member, driving mechanism therefor including relatively rotatable transmission shafts, operative driving 25 connections between one of said shafts and said feed member, means for effecting rotation of the other of said shafts including a friction controlling clutch, means including interlocking clutch plungers carried by one of 30 said shafts for connecting said shafts directly together, and clutch operating means for insuring release of said friction clutch and thereafter release of said clutch plungers to permit free relative rotation between said 35 shafts.

24. In a mining machine feeding mechanism, the combination of a feed member, driving mechanism therefor including relatively rotatable transmission shafts arranged in 40 concentric relation one within the other, operative driving connections between one of said shafts and said feed member, means for effecting rotation of the other of said shafts including a friction controlling clutch, means 45 including interlocking clutch plungers carried by one of said shafts for connecting said shafts directly together, and clutch operating means for insuring release of said friction clutch and thereafter release of said clutch 50 plungers to permit free relative rotation between said shafts.

In testimony whereof I affix my signature.
MORRIS P. HOLMES.
